UNITED STATES PATENT OFFICE.

MORRIS FORD SMITH, OF PHILADELPHIA, PENNSYLVANIA.

FIREARM.

1,077,103.

Specification of Letters Patent.

Patented Oct. 28, 1913.

Application filed December 14, 1911. Serial No. 665,709.

To all whom it may concern:

Be it known that I, MORRIS FORD SMITH, a citizen of the United States, and resident of Philadelphia, in the State of Pennsylvania, have invented certain new and useful Improvements in Firearms, of which the following is a specification.

An object of the present invention is to provide improvements in that class of fire 10 arms known as magazine fire arms, whether used for sporting or military purposes.

Specifically, one object of the present invention is to provide a novel form of connection between the two main parts of the 15 fire arm, to simplify the disassembling or "take down" of the gun to render it more portable.

Another specific object is to provide a safety lock for the action sleeve which will 10 prevent the same being retracted by the hand of the gunner until after firing, and hence rendering the fire arm more safe.

A further specific object is to provide means in the firing mechanism whereby the 5 aforesaid action sleeve is unlocked immediately the gun has been fired.

A further specific object is to provide an improved sear safety dog whereby the firing mechanism may be thrown out of operation.

A still further specific object is to provide a simple form of action slide and a simple connection between the action slide, the breech bolt, and the firing pin whereby on moving the slide rearward, there is first a relative movement between the slide and breech-bolt, whereby the firing pin is withdrawn to safety position and the breech-bolt is rotated to unlock it after which the continued rearward movement withdraws the breech-bolt to open the breech, throw out the spent shell and admit a new cartridge in advance of the breech-bolt; whereas on reversing the slide, the first part of the forward movement closes the breech, pushing in a new cartridge in advance, while the latter part of the slide's forward movement, rotates the breech-bolt to lock it, and clears the path for the firing pin, to permit it to reach the primer only after the slide has moved far enough to insure complete locking of the breech bolt.

In the drawings, Figure 1 is a general outside view of a fire arm embodying my invention; Fig. 2 is a similar view, enlarged and partly in section, showing the gun

partly broken to illustrate the "take down"; Fig. 3 is a longitudinal section of the gun showing the parts in their positions at the moment the hammer hits the firing pin; Fig. 4 is a like view illustrating the position of the parts when the action sleeve has been retracted to open the breech and eject the cartridge; Fig. 5 is a detail longitudinal, sectional view illustrating the action slide lock; Fig. 6 is a detail view of the reciprocating and rotatory breech bolt; Fig. 7 is an end view of the same showing its locking lugs; Fig. 8 is a detail view of the action sleeve locking lever; Fig. 9 is an isometric projection of the hammer, minus its spring pressed detent; Fig. 10 is a detail view of the hammer detent; Fig. 11 is an isometric projection of the combined trigger and sear, with the sear safety dog removed from its recess; Fig. 12 is a detail view of the sear safety dog removed from its recess in the combined trigger and sear and showing the inner face of said dog; and Fig. 13 is a plan view of the combined trigger and sear and sear safety dog assembled.

Referring now in detail to my invention, 1 represents the stock of the gun, 2 the frame provided with rearwardly projecting tangs to receive the stock 1, 3 the receiver and 4 the barrel of the gun, screw threaded in the forward end of the receiver 3 in the usual manner.

"Take down".—For the sake of convenience in carrying, when not in use, a fire arm of this type is ordinarily separable into two main parts, one of which comprises the stock and the frame with their attachments, while the other comprises the barrel and the receiver with their accessories. The "take down" of the present gun is provided for through means of a transverse pin 5 extending across a suitable socket 5^a in the forward part of the frame; a hook-shaped lug 6 depending from a ring 7 encircling the rear portion of the barrel 4, which lug fits laterally between the walls of the socket 5^a, and by interengaging with the pin 5, serves to position the two main parts of the gun at that point and prevent forward movement of the barrel on the frame; also a locking plunger or bolt 9 fitted within a socket 8 at the rear end of the receiver, normally projected by a spring 10, but limited in its movement by a lug 11, working in a slot 12, and adapted, when the two major gun parts are closed together, to snap into

a keeper or recess 13 formed in the abutment on the frame 2; a displacing plunger 15 having a shank 16, and terminating in a push button 17, being arranged to displace the locking plunger 9 to permit the rear end of the receiver to swing up out of the frame when it is desired to separate the main parts of the gun. The bevel on the protruding end of the locking plunger is sufficient to 5 displace the plunger inward while the parts are being swung into assembled relation, and the barrel stands at the angle shown in Fig. 2. When said locking plunger has snapped into its seat, the angle of the bevel 10 is not sufficient to deflect the plunger under any upward tendency of the barrel.

The action.—The receiver is provided with rearwardly extending guide-slots 18 adapted to receive the laterally projecting lugs 19 on the combined reciprocating and rotatory breech bolt 20 to restrain the latter from rotation during its reciprocating, opening or closing movement. The locking lugs 19 on the breech bolt 20 are adapted to 20 engage, when the breech bolt is in closed position, with corresponding locking lugs 21 on the receiver within the barrel socket or recess. The breech bolt 20 is provided with oppositely inclined cam slots 22 which receive the transverse pin 23 carried by an action slide or sleeve 24, which slides on the outside of the barrel 4 and the receiver 3 and projects forwardly a sufficient distance along the barrel 4 to receive, in the proper 25 position, an action grip or handle 25 which is mounted on said sleeve through the medium of a stud 26 embedded in the action grip or handle 25 and secured therein by a longitudinally extending pin 27. The stud 30 26 is secured to the action sleeve 24 through means of a dove-tailed lug or projection 28 thereon. In order that the barrel portion of the bearing for the sliding sleeve 24 may be of the same diameter throughout its length, 35 the contracted forward portion of the barrel may be built up by a sleeve 29 screw threaded to the barrel and abutting the rear enlarged portion of the barrel. This sleeve extends toward the muzzle of the barrel a suitable distance to support the action sleeve 24 40 in its forward locked position. The pin 23 which extends from one side of the action sleeve to the other is perforated to receive, and permits a sliding engagement with, the forward contracted portion or needle of the 45 firing pin 30. It, however, stands in such relation to the body of the firing pin as will prevent the firing pin reaching the primer until the pin 23 has moved forward a sufficient distance to insure locking of the breech bolt. It thus renders the gun incapable of 50 firing until the breech bolt is locked. The firing pin 30 is as usual mounted within the bolt 20 and is held in its forward position 55 against the head of the cartridge by a spring

31 pressing against the usual annular shoulder on the firing pin and the firing pin when in such forward position projects slightly rearwardly beyond the bolt in position to be struck by the hammer hereinafter described. 70

The function of the firing pin spring is merely to permit relative movement between the bolt and the firing pin upon movement of the action sleeve so that there will be requisite lost reciprocating motion of the breech bolt during the turning or unlocking movement of the same; this spring being adapted to immediately thrust the firing pin forward when it is permitted to do so by the return of the action sleeve to its forward 80 position.

In its forward position the action sleeve 24 is locked against unintentional rearward movement by the hand of the gunner, or rebound, of the action sleeve 24 through 85 means of a pivoted lever 32 of the first order mounted in a recess in the upper face of the receiver having a hook-shaped or notched sleeve-engaging arm 33 with a finger button formed thereon and which is normally pressed upwardly into engagement with the rear end or edge of the action sleeve by a leaf spring 34 in the sleeve locking lever recess and seated in the receiver, exerting pressure on the opposite arm of the lever 35. 95 Normally therefore the tendency of the notched or hook-shaped arm 33 of the locking lever 32 is upward so that it springs out of its recess immediately the action sleeve 24 has passed it on the return of the sleeve 100 24 to its forward position. When this occurs, the rear edge of the action sleeve enters the notch in the locking lever, but since this notch is of a depth equal only to substantially the thickness of the action sleeve 105 at its rear edge, excessive upward movement of the notch arm of the lever or movement beyond the upper surface of the receiver will be restrained by the action sleeve, so that, when in locking position, the locking 110 lever engages both the rear edge of the action sleeve and the rear wall of its recess in the receiver. Hence strain on the locking lever is borne by the rear wall of the locking lever recess instead of the pivot of 115 the lever.

The hammer 36 is illustrated as a substantially segmental shape and is provided with a striking face 37, a laterally projecting hub 38 of proportionately great diameter and about which the hammer operating spring 39 is suitably wound and secured to the hammer to give the spring greater leverage in operating the hammer. The spring 39 at its lower end engages the frame 2 of the gun, bearing against the bottom of the hammer recess 40 in the receiver. Depression of the hammer 36 tensions the spring 39. The hammer 36 is mounted on a pivot 41 which is supported in the frame 2 of the 125 gun, bearing against the bottom of the hammer recess 40 in the receiver. Depression of the hammer 36 tensions the spring 39. The hammer 36 is mounted on a pivot 41 which is supported in the frame 2 of the 130

gun and extends in the hammer recess 40. The hammer is provided with a recess 42 in its outer face which receives a hammer detent 43 and its actuating spring 44, the detent 43 being secured with limited movement within said recess 42 through the medium of a notch 45 in the detent 43 and a pin 46 extending transversely through the hammer 36 and through the notch 45. The detent 40 actuating spring 44 is held in its socket by the detent.

47 is the sear which in the present instance constitutes a forwardly projecting integral portion of the trigger 48 sliding in a suitable guide-way 49 formed in the frame 2 adjacent the trigger slot 50. This combined sear and trigger is normally pressed forward, so that the sear projects in the hammer recess 40, by a spring 51, seated in a recess in the rear face of the trigger 48 and bearing against the rear face of the trigger slot 50. Thus a single spring is made to answer for the trigger and the sear.

The rear portion of the sear 47 or the forward portion of the trigger 48 is recessed at 52 to receive a sear safety dog 53 pivoted on a pin 54 which extends through an opening or slot 55 in the rear portion of the sear 47 or forward portion of the trigger 48 and which pivot 54 is fixedly mounted in the side walls of the frame 2 of the gun. The opening or slot 55 is of sufficient length to permit slight movement of the sear 47 with relation to the sear safety dog 53 so that relative movement between the sear and the safety dog will be permitted when the dog is in non-operative position.

The sear safety dog 53 is provided with a forwardly extending engaging nose 56 which normally, or when the sear safety dog 53 is in non-operative position and at each retraction of the sear 47, enters a corresponding notch or recess 57 in the forward wall of the sear safety dog recess 52 and thus permits relative movement between the sear 47 and the sear safety dog 53. Beneath the notch 57 is an engaging face 58 which when the dog is in safety or engaging position is engaged by the projecting nose 56 on the dog. The dog is held in either one of its adjusting positions by a plunger 59 in a suitable socket 60 in the sear and pressed outwardly into engagement with suitable "on" and "off" notches 61 and 62 in the face of dog 53 by a spring 63 coiled about the plunger and housed in the socket 60. "Off" notch 62 is elongated to allow relative longitudinal movement between dog 53 and sear 47 but prevent pivotal movement of dog 53. "On" notch 61 is circular as when plunger 59 is in engagement therewith, i.e. relative movement between dog 53 and sear 47 is possible. To permit reciprocating movement of plunger 59 a recess 64 is formed in the frame 2 of the gun in line

with socket 60 and recess 64 is elongated to allow relative longitudinal movement between dog 53 and sear 47. Thus the sear safety dog is prevented from being thrown out of either of its adjusted positions by 70 jolt or recoil of the gun.

It is manifest that when the thumb piece of the sear safety dog 53 is pulled toward the trigger, the engaging end 56 will be pulled out of alignment with the notch 57 and into line with the engaging face 58 on the sear 47 so that the retraction of the sear to release the hammer 36 will be impossible. This is because the pivot pin 54 of the sear safety dog 53 is fixed immovably in the 80 frame 2 of the gun.

I claim:—

1. In a gun, the combination with the receiver and the frame of the gun, of a recessed bolt mounted to lock the frame and receiver to each other and a breech bolt mounted to operate in the recess in said locking bolt. 85

2. In a gun, the combination with the receiver and the frame of the gun, of a recessed bolt mounted to lock the frame and receiver to each other, and a breech bolt mounted to operate at the extreme of its retraction movement in the recess in said locking bolt. 90

3. In a gun, the combination with the two main parts of the gun, a breech bolt movably mounted on one of said parts and a recessed locking device acting rearwardly and, mounted on said same part in position to receive in its recess said breech bolt at one of the extreme positions of said bolt. 95

4. In a gun adapted to be broken in its vertical longitudinal plane when taken down, a barrel carrying receiver having at its rear end a suitable socket and a spring projected locking bolt mounted in said socket and acting rearwardly in the gun in combination with the frame of the gun and a bolt retracting device mounted on the frame in line 110 with said bolt. 105

5. In a gun, the combination with a frame having a recess therein, and a depressible plate mounted in said recess, in combination with the receiver, an automatically projected tubular bolt housed in the rear end of said receiver and normally impinging against said plate. 115

6. In a gun, the combination with a frame having a recess therein, and a depressible plate mounted in said recess, in combination with the receiver, an automatically projected tubular bolt housed in the rear end of said receiver and normally projecting into said recess and engaging said plate. 120

7. In a gun adapted to be broken in its vertical longitudinal plane when taken down, a frame and a barrel carrying receiver having adjacent recesses, a locking device mounted in one of said recesses acting rearwardly 130

- and parallel to the axis of the gun, and an actuating device mounted in the other of said recesses and engaging the locking device.
5. In a gun adapted to be broken in its vertical longitudinal plane when taken down, a frame and a barrel carrying receiver having adjacent recesses, a locking device mounted in one of said recesses and adapted to project into the other of said recesses in a rearward direction parallel to the gun axis, and an actuating device mounted in said other recess and adapted to displace the locking device therefrom.
10. In a gun, a frame having a recess therein and a movable plate mounted in said recess, in combination with the receiver, an automatically actuated tubular bolt housed in the rear end of said receiver and normally engaging said plate, and the breech bolt mounted to enter said tubular locking bolt.
15. In a gun, the combination with an action sleeve, of a laterally perforated breech bolt, a connecting pin carried by said action sleeve, extending through said breech bolt in position to impinge against the firing pin and a firing pin mounted within said bolt.
20. In a gun, the combination with an action sleeve, of a laterally perforated breech bolt, a connecting pin carried by said action sleeve, extending through said breech bolt and perforated to receive the firing pin and a firing pin mounted within said bolt and extending through said connecting pin.
25. In a gun, the combination with an action slide and a breech bolt having elongated transverse perforations of helical shape, of a connecting pin carried by and extending from side to side of the action sleeve through the elongated transverse perforations in the breech bolt, said connecting pin being perforated across its axis, a firing pin mounted within the bolt and a striking needle seated in said firing pin and slidably seated in the perforation in the connecting pin.
30. In a gun, the combination with the action slide, the receiver having locking lugs, and a breech bolt having transverse perforations of helical shape, of a connecting pin extending from one side of the action sleeve to the other through said perforations in the breech bolt; a spring pressed firing pin mounted in the breech bolt, and a striking needle carried by said firing pin and mounted to slide in the perforation in said cocking pin.
35. In a gun, the combination with the action slide, the receiver having locking lugs and a breech bolt having transverse perforations of helical shape, of a connecting pin extending from one side of the action sleeve to the other through said perforations in the breech bolt; and having a perforation across its axis, said perforations in the breech bolt being longitudinally elongated and oppositely inclined whereby movement of the pin therein rotates the breech bolt to unlock it, a spring pressed firing pin mounted in the breech bolt, and a striking needle carried by said firing pin and mounted to slide in the perforation in said cocking pin.
40. In a gun, a hammer, a detent yieldingly mounted to slide in said hammer, and a combined trigger and reciprocating sear non-yielding as to the detent but adapted to be retracted to release the detent of the hammer, a hub on the hammer and a spring coiled around said hub for oscillating the hammer, said hammer being of segmental shape with a straight striking surface.
45. In a gun, a combined trigger and reciprocating sear having a recess therein, and a sear safety dog located in said recess.
50. In a gun, a combined trigger and reciprocating sear having a recess therein and a sear safety dog located in said recess and movable independently of the sear.
55. In a gun, a reciprocating sear, a sear safety dog, movable into and out of dogging relation to the sear, and a detent carried by the sear in position to engage said dog and hold it in the position to which it is adjusted.
60. In a gun, a reciprocating sear, a sear safety dog, movable into and out of dogging relation to the sear, and a detent carried by the sear in position to engage said dog and hold it in the position to which it is adjusted, said dog having two seats for said detent for holding the dog in its respective positions.
65. In a gun, a reciprocating sear, a sear safety dog, movable into and out of dogging relation to the sear, and a detent carried by the sear in position to engage said dog and hold it in the position to which it is adjusted, said dog having two seats for said detent for holding the dog in its respective positions, one of said seats being elongated to permit relative movement between the sear and dog when the latter is out of dogging position.
70. In a gun, a reciprocating sear, a sear safety dog, movable into and out of dogging relation to the sear, and a detent carried by the sear in position to engage said dog and hold it in the position to which it is adjusted, said dog having two seats for said detent for holding the dog in its respective positions, one of said seats being elongated to permit relative movement between the sear and dog when the latter is out of dogging position.
75. In a gun, a reciprocating sear, a sear safety dog, movable into and out of dogging relation to the sear, and a detent carried by the sear in position to engage said dog and hold it in the position to which it is adjusted, said dog having two seats for said detent for holding the dog in its respective positions.
80. In a gun, a reciprocating sear, a sear safety dog, movable into and out of dogging relation to the sear, and a detent carried by the sear in position to engage said dog and hold it in the position to which it is adjusted, said dog having two seats for said detent for holding the dog in its respective positions.
85. In a gun, a reciprocating sear, a sear safety dog, movable into and out of dogging relation to the sear, and a detent carried by the sear in position to engage said dog and hold it in the position to which it is adjusted, said dog having two seats for said detent for holding the dog in its respective positions.
90. In a gun, a reciprocating sear, a sear safety dog, movable into and out of dogging relation to the sear, and a detent carried by the sear in position to engage said dog and hold it in the position to which it is adjusted, said dog having two seats for said detent for holding the dog in its respective positions.
95. In a gun, a reciprocating sear, a sear safety dog, movable into and out of dogging relation to the sear, and a detent carried by the sear in position to engage said dog and hold it in the position to which it is adjusted, said dog having two seats for said detent for holding the dog in its respective positions.
100. In a gun, a reciprocating sear, a sear safety dog, movable into and out of dogging relation to the sear, and a detent carried by the sear in position to engage said dog and hold it in the position to which it is adjusted, said dog having two seats for said detent for holding the dog in its respective positions.
105. In a gun, a reciprocating sear, a sear safety dog, movable into and out of dogging relation to the sear, and a detent carried by the sear in position to engage said dog and hold it in the position to which it is adjusted, said dog having two seats for said detent for holding the dog in its respective positions.
110. In a gun, a reciprocating sear, a sear safety dog, movable into and out of dogging relation to the sear, and a detent carried by the sear in position to engage said dog and hold it in the position to which it is adjusted, said dog having two seats for said detent for holding the dog in its respective positions.
115. In a gun, a reciprocating sear, an oscillating safety dog, a detent carried by the sear, traveling with the sear, and movable into and out of the path of recesses in the safety dog.
120. In a gun, a reciprocating sear having a recess therein, a sear safety dog mounted in said recess and movable into and out of dogging position, and a detent carried by the sear in position to engage the sear safety dog and hold the same in the position to which it is adjusted.
125. In a gun, the combination with a reciprocating sear having a recess therein, a sear safety dog movably mounted in said recess and a spring pressed detent carried by the sear in position to engage the sear.

safety dog and hold the same against displacement.

24. In a gun, the frame with a recess, a reciprocating sear, a sear safety dog and a 5 sear safety dog detent carried by the sear and projecting into said recess to permit movement of said detent.

25. In a gun, the frame with an elongated recess, a reciprocating sear, a sear safety 10 dog, a sear safety dog detent carried by said sear and projecting into said recess to permit movement of said detent incident to retraction of the sear.

26. In a gun, a reciprocating sear, a pivot 15 pin extending through said sear and a sear safety dog mounted on said pin.

27. In a gun, a sear, a pivot pin extending through said sear and having a fixed bearing outside the sear and a sear safety 20 dog mounted on said pin.

28. In a gun, a movable sear having an opening, elongated in the direction of movement of the sear, a pivot pin having fixed bearings outside the sear and extending 25 through said opening and a sear safety dog mounted on said pin.

29. In a gun, a slidingly supported integral trigger and sear, a recess in the sear, and a sear safety dog in said recess.

30. In a gun, a sliding sear, a recess in the sear, a sear safety dog in said recess and a trigger projecting rigidly from said sear.

31. In a gun, a slidingly supported sear, a recess in the sear and a sear safety dog 35 in said recess a trigger projecting rigidly therefrom, and a spring for projecting both said trigger and sear.

32. In a gun, the combination with a hammer, a spring pressed, normally projected 40 hammer detent mounted in said hammer, a reciprocating sear engaged by said detent to hold the hammer cocked and movable to disengage said detent to release the hammer, an extension on the sear forming a 45 trigger, a spring to project the sear, a recess in the sear and a sear safety dog in said recess.

33. In a gun, an action slide seated around the gun barrel, an automatically projecting action slide lock, and a member 50 moving on firing and retracting said lock and located beneath said lock.

34. In a gun, an action slide seated around the gun barrel, an automatically projecting action slide lock and a firing striker 55 withdrawing said lock, when the striker moves to fire the gun said striker located beneath said lock.

35. In a gun, the combination with an 60 action slide seated around the gun barrel, a lock for locking said slide at the moment of firing and a pivoted hammer arranged beneath said lock to release the slide from its lock when the gun is fired.

36. In a gun, the combination with an 65 action slide seated around the gun barrel, a lock for locking said slide at the moment of firing and a pivoted hammer beneath said lock having a cam arranged to release the slide from its lock when the gun is fired. 70

37. In a gun, the combination with an action slide seated around the gun barrel, a receiver, having a recess, a lever mounted in the recess in the receiver, a spring for projecting said lever to engage the action 75 slide when the latter is in forward position, a hammer beneath said lever and a projection on the hammer adapted to strike said lever and displace it from said slide, when the gun is fired. 80

38. In a gun, the combination with a sleeve forming part of an action slide, a receiver having a suitable recess therein, a slide locking lever having an intermediate pivot securing it in said recess, a spring 85 tending to rock said lever to project one end into the path of said sleeve at the moment the slide reaches its forward position, a pivoted hammer located beneath said lever and a cam projection on said hammer in position to strike the end of said lever opposite its sleeve-engaging end and disengage the lever from the action sleeve at the moment the gun is fired. 90

39. In a gun, the combination with an action slide, of a locking lever having a projection adapted to engage and lock said slide, said projection being formed as a lever releasing button. 95

40. In a gun, the combination with an action slide, of a locking lever having a projection adapted to engage and lock said slide, said projection being formed as a releasing button and a spring for forcing said lever into engagement with said slide. 100 105

41. In a gun, an action slide seated around the gun barrel, a slide locking lever of the first order, one arm adapted to engage said slide to lock the same and the other arm adapted to be actuated to cause disengagement, a spring acting upon said other arm in direction of locking, and a firing hammer acting on the under side of said other arm for unlocking. 110

42. In a gun, an action slide, a slide locking lever of the first order, having one arm adapted to engage said slide to lock the same and projecting within reach of the finger for voluntarily releasing it and the other arm projecting into position for automatic 120 control, a spring for actuating said other arm in the direction to cause engagement of the action slide, means actuated on firing adapted to displace said other arm, in opposition to the spring to release said engagement. 125

43. In an action slide for guns seated around the gun barrel, a stud or projection

on said slide, a grip, block or handle embracing said stud or projection and a pin extending through said grip or handle and said projection.

5 44. In a gun, an action slide seated around the gun barrel, a stud or projection on said slide, a grip block or handle embracing said stud or projection and a longitudinal pin

extending through said grip or handle and said projection.

The foregoing specification signed at Washington D. C. this 5th day of July, 1911.

MORRIS FORD SMITH.

In presence of—

HERVEY S. KNIGHT,

EDWIN S. CLARKSON.
